UNITED STATES PATENT OFFICE

2,377,329

END MILL

Alfred B. Dettmer, Cleveland, Ohio, assignor to
The Weldon Tool Company, a corporation of
Ohio

Application April 1, 1944, Serial No. 529,049

8 Claims. (Cl. 29—103)

My invention relates generally to milling tools and more particularly to fluted end mills and the like.

An object of my invention is to provide an end mill having flutes disposed to cut towards the end of the mill and having end cutting tips disposed to cut away from the end of the mill.

Another object of my invention is the provision, in an end mill having a plurality of flutes spiraling toward the end of the mill, of cutting tips which cut in the direction opposite to the direction cut by the flutes.

Another object of my invention is the provision of an end mill having longitudinal flutes producing an endward cutting action, and having an end portion of non-clogging cutting edges.

Another object of my invention is to provide an end mill having a plurality of flutes spiraling in a direction opposite the direction in which the end mill is disposed to rotate, and having a cutting end with an angle of rake opposite to the angle of the spiral flutes.

Other objects and a fuller understanding of my invention may be had by referring to the following description and claims taken in conjunction with the accompanying drawing, in which:

Figure 1 is a longitudinal view of a type of end mill embodying the features of my invention;

Figure 2 is a longitudinal view of a type of end mill embodying the features of my invention shown at right angles to Figure 1;

Figure 3 is a perspective view of the end of an end mill embodying the features of my invention; and

Figure 4 is a view of an mill embodying the features of my invention shown in a cutting position on a work piece.

With reference to Figure 1 and Figure 2 of the drawing, I illustrate a type of end mill 10 embodying the features of my invention and comprising generally a shank portion 11 and a fluted portion 12 having end cutting tips 16 and 17. The end mill 10 is disposed to rotate about an axis in the direction indicated by the directional arrow 13. The shank portion 11 has flat surfaces 30 and 31 to facilitate the holding of the end mill 10 in a driving device. The fluted portion 12 has two flutes 14 and 15 thereon. The flutes 14 and 15 on the fluted portion 12 spiral endwardly away from the shank portion 11 in a direction opposite that of the direction of rotation of the mill 10. At the end of the fluted portion 12 are two fluted cutting tips 16 and 17 which spiral about the fluted portion 12 in a direction opposite the direction which the flutes 14 and 15 spiral about the

fluted portion 12. The tips 16 and 17 extend a short distance from the end rearwardly toward the shank portion 11 and are axially co-extensive with the flutes 14 and 15 over part of their length.

As shown in Figures 1 and 2 of the illustration, the flutes 14 and 15 are integral with the end mill and are extended in a spiral manner along the fluted portion 12. It is noted in Figure 4 that the spiral flutes 14 and 15 terminate a short distance rearwardly of the extreme end of the mill 10. However, the flutes 14 and 15 are extended far enough endwardly that they become axially co-extensive with the cutting tips 16 and 17. In Figure 3 the butt ends of flutes 14 and 15 are shown on surfaces 19 and 18 respectively. Each flute, such as flute 14, has an undercut side 32 and a backing side 33 which converge to form a longitudinal cutting edge 23. The flute 15 has a cutting edge 22 formed similarly to cutting edge 23 of flute 14. The backing side 33 for both of the flutes has a first cutting clearance 26 generally termed the first backoff clearance and a second cutting clearance 34 generally termed the second backoff clearance. The combination of first and second backoff is called a double backoff clearance. The contour of the undercut side 32 is arcuate so that the undercut side 32 extends outwardly from the valley between the flutes in a curve to the longitudinal surface 34.

As the mill 10 rotates in the direction indicated by directional arrow 13, the cutting edges 22 and 23 of the flutes 15 and 14 produce a downward slicing cutting action on the material being cut. The downward cutting action is highly beneficial because it does not chip or tear the corner of the work piece cut by the tool, such, for example, as the corner 45 of the work piece 46, see Figure 4. However, it is difficult to form satisfactory end cutting edges on downward cutting flutes such as those described herebefore. Therefore, at the end of the mill 10 furthermost removed from the driving engagement shank portion 11, I provide the cutting tips 16 and 17. The structure and position of the cutting tips 16 and 17 can be seen in Figure 3 of the drawing. As shown in Figure 3, the cutting tips 16 and 17 have longitudinal cutting edges 25 and 24. The cutting edges 25 and 24 have radial diameters equal to the radial diameters of cutting edges 22 and 23 of flutes 14 and 15. The cutting edges 25 and 24 of tips 16 and 17 also have a double backoff clearance as herebefore described. The surfaces of the double backoff clearance of the longitudinal cutting edges 25 and 24 of cutting tips 16 and 17 are shown in Figure 3 by reference characters 40 and 41.

The cutting tips 16 and 17 are also provided with transverse cutting edges 36 and 37 having their inner ends diametrically separated from one another by a clearance 35. A double backoff clearance, as herebefore described, is provided for the cutting edges 36 and 37. The surfaces of the double backoff of the transverse cutting edges 36 and 37 are shown in Figure 3 by reference characters 20 and 38 on the tip 17 and by reference characters 21 and 39 on the tip 16. Both tips 16 and 17 may have raking surfaces 50 disposed parallel to the axis of rotation of the end mill 10 providing substantially a zero rake angle or the raking surfaces 50 may incline at a predetermined rake angle with the axis of the mill 10. I illustrate the raking surface 50 of the cutting tips 16 and 17 as being inclined or spiraling at a rake angle of substantially 20° with the axis of rotation of the end mill.

The operation of my end mill will be better understood by referring to Figure 4 of the drawing in which the directional arrow line 43 indicates the direction of rotation of a type of an end mill 10 conforming to my invention. As rotation of the end mill 10 takes place, the longitudinal cutting edge 23 of the spiral flute 14 engages the top corner 45 of the material 46 being machined. With continued rotation of the mill 10, the cutting edge 23 cuts downwardly along the surface 47 of the material 46 as indicated by a directional arrow 48, whereby any severed chips or shavings are pushed downwardly toward the cutting tips 16 and 17 of the end mill 10. The downward cutting action described produces a clean sharp corner, at 45, instead of tearing same which would be the case with an upward cutting action, because of the lack of a supporting mass behind the corner. At the end of the mill, the longitudinal cutting edges 24 and 25 of the cutting tips 16 and 17 are disposed to sever material from the surface 47 of the material 46 at the inside corner 51.

The longitudinal cutting edges 24 and 25 will cut on the surface 47 because the edges 24 and 25 have a circular diameter equal to the circular diameter of the longitudinal cutting edges 22 and 23 of spiral flutes 14 and 15. Furthermore, the surface 47 is disposed to be continuous because the longitudinal cutting edges 24 and 25 of the cutting tips 16 and 17 extend toward the shank portion 11 far enough to overlap or become axially co-extensive with the longitudinal cutting edges 22 and 23 of the spiral flutes 14 and 15.

The transverse cutting edges 36 and 37 of the cutting tips 16 and 17 are disposed to sever material from the bottom surface 49 of the material 46 and define a good sharp inside corner 51. Any chips or shavings removed by the longitudinal cutting edges 24 and 25 or transverse edges 36 and 37 of the cutting tips 16 and 17 are carried upwardly on the upward slanting or raking surfaces 50 of the cutting tips 16 and 17.

The upward movement of the severed chips and shavings described removes the severed mass from the end cutting edges 36 and 37 and thus prevents clogging of the cutting tips.

In my invention the cutting flutes of the tool cut the work piece in a direction towards the end of the mill. Accordingly, the reaction of the tool upon the spindle which holds the shank portion 11 is such as to force the spindle away from the work piece while at the same time the reaction of the tool on the work piece is such as to force the work piece against the bed plate or fixture holding the work piece. The opposing reactions

upon the spindle and the work piece prevent vibration which would otherwise occur if the cutting flutes cut the work piece in a direction away from the end of the tool.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. An end mill comprising a driving engagement portion and a fluted portion having a cutting end, said end mill being adapted to rotate in a certain direction as viewed from the driving engagement portion, said fluted portion having spiral flutes beginning at the driving engagement portion and spiraling towards the cutting end in a direction opposite to that of rotation of the end mill, said fluted portion having a plurality of cutting tips at the cutting end thereof, said flutes and tips having longitudinal cutting edges extending therealong, and said tips also having transverse cutting edges at the cutting end thereof.

2. An end mill comprising a driving engagement portion and a fluted portion having a cutting end, said end mill being adapted to rotate in a certain direction as viewed from the driving engagement portion, said fluted portion having spiral flutes beginning at the driving engagement portion and spiraling towards the cutting end in a direction opposite to that of the rotation of the end mill, said cutting end having a plurality of fluted cutting tips at the end thereof disposed to spiral towards the end of the mill in a direction opposite to that of the said spiral flutes, said flutes and tips having longitudinal cutting edges extending therealong and being axially co-extensive over part of their length, said tips also having transverse cutting edges at the cutting end thereof.

3. An end mill comprising a driving engagement portion and a fluted portion, said fluted portion having at least two flutes annularly spaced by an angle of substantially 180° and having a fluted cutting end, said end mill being adapted to rotate in a certain direction as viewed from the driving engagement portion, said fluted portion having spiral flutes beginning at the driving engagement portion and spiraling towards the cutting end in a direction opposite to that of the rotation of the end mill, said fluted cutting end having tips with longitudinal and transverse cutting edges and being disposed between the said flutes and also being annularly spaced from one another by an angle of substantially 180°, the said longitudinal cutting edges of the cutting tips and of the flutes being axially coextensive over part of their length.

4. An end mill having in combination, a plurality of flutes with longitudinal cutting edges extending therealong and a plurality of fluted cutting tips located at the end thereof, said flutes and cutting tips spiraling co-axially in opposite directions and said tips also having transverse cutting edges at the cutting end thereof.

5. An end mill comprising a driving engagement portion and a fluted portion having a cutting end, said end mill being adapted to rotate in a certain direction as viewed from the driving engagement portion, said fluted portion having spiral flutes beginning at the driving engagement

portion and spiraling towards the cutting end in a direction opposite to that of the rotation of the end mill, said cutting end having a plurality of cutting tips at the end thereof, said flutes and tips having longitudinal cutting edges extending therealong and said tips also having transverse cutting edges, said tips and said flutes having longitudinal cutting edges disposed to cut in opposite axial directions.

6. An end mill adapted to rotate in a certain direction, and having flutes spiraling towards the cutting end in a direction opposite to that of the rotation of the end mill, said end mill having a plurality of cutting tips at the cutting end thereof, and spiraling co-axially with, and in an opposite direction to that of the flutes and said tips also having transverse cutting edges at the cutting end thereof.

7. An end mill adapted to rotate in a certain direction, and having flutes spiraling towards the cutting end in a direction opposite to that of the rotation of the end mill, said end mill having a plurality of cutting tips at the cutting end thereof, and disposed between the flutes.

8. An end mill having a plurality of flutes with longitudinal cutting edges spiraling toward the cutting end of the mill, and having a plurality of cutting tips disposed between the flutes at the cutting end of said mill, said tips having transverse cutting edges at the end thereof and having longitudinal cutting edges co-axial with the longitudinal cutting edges of said flutes.
